UNITED STATES PATENT OFFICE.

FRED BECKER, OF BUFFALO, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed August 9, 1921. Serial No. 490,863.

To all whom it may concern:

Be it known that I, FRED BECKER, a citizen of the Republic of Switzerland, residing in Buffalo, in the county of Erie and State 5 of New York, have invented certain new and useful Improvements in Typewriting Machines, of which the following is a specification.

This invention relates to typewriting machines, and more particularly to work-sheet controlling devices, and is herein disclosed as applied to an Underwood Standard typewriting machine.

Heretofore for adjusting work-sheets for 15 certain kinds of work, provision has been made of an aligning table placed above the platen and adjustable to different line-space positions with reference to the printing line and to different letter-space positions along 20 the platen. The adjustments for line-space position and letter-space position have usually been entirely independent, and such adjustments have been made at comparatively long intervals, a considerable number 25 of work-sheets or cards being inserted and typed before a change of adjustment has become necessary.

In some classes of work it becomes necessary to shift the aligning table quickly, as, 30 for example, when an entry is to be made in one line on a work-sheet when the aligning table is in one letter-space position along the platen, and in another line when the table is in another letter-space position relative 35 to the platen. Such conditions may arise in writing bills in connection with typing on other sheets in a combined typewriting and computing machine such, for example, as an Underwood-Hanson bookkeeping machine.

40 There may be two separate operations in preparing a bill. The bill may be rapidly inserted at the front of the other work-sheet and positioned by the aligning table which has been adjusted in the proper position. 45 After completing the typing on the first line, which may be of descriptive matter with certain computations, the aligning table may be released and shifted quickly to the position for typing on the second line, the 50 change in letter-space position of the aligning table being necessary in order to enable the machine to effect tabulation or computation in the manner desired. In bookkeeping machines of the type referred to, the 55 computing zones and form of computation

therein are determined by the carriage in accordance with the setting of denomination selectors or dogs, and, inasmuch as considerable time would be required to reset the selectors, there is a very great advantage in 60 the use of a device by which the equivalent of a resetting of the selectors may be obtained by shifting the work-sheet lengthwise of the platen. Obviously in work of this sort, it is necessary to shift the aligning table rapidly from one position to another. 65

In other classes of work it is desirable for an operator, in the course of a day, to make more or less frequent entries of computation or tabulation upon different forms or 70 sheets having certain dissimilar characteristics; such, for instance, as variations in line-length, or distance, between a side edge of a sheet, usually gaged at or adjacent one end of the platen, and the portion of the 75 sheet desired to be located within the computing zone or at a fixed columnar or tabulating position; or variations in the line-spacing or distance, between the top edge and first writing line in different work-sheets; or variations in both line-length and 80 line-spacing in different types of sheets.

Also in still other classes of work it is desired at different times to make corresponding 85 sets of entries in different columnar positions on work-sheets of one type; or in the same columnar position on work-sheets of dissimilar character, as hereinabove mentioned; or in different positions on work-sheets of dissimilar types. These conditions 90 may be met by the provision of means for making more or less frequent adjustments for the accommodation of different sheets either by effecting alterations in the gaging means or in the mechanical devices utilizable 95 for setting the tabular or computing mechanism, or in both gaging and mechanical setting. For overcoming difficulties incident to such adjustments, a simplified device is provided of the character set forth herein, including a line-finder for quickly locating the writing line and a zone-finder for quickly locating the desired columnar location or zone; the line-finder and zone-finder being 100 operatively associative as a combined line-finder and zone-finder for quickly locating a work-sheet in any predetermined writing position.

The main object of the invention is to 110 provide means to enable an aligning table to

be rapidly shifted from one letter-space and line-space position to another, for the purposes stated and for analogous purposes. A further feature is the provision of means to enable the work-sheet to be held to the aligning table and moved with the table from one position to another. Still another feature enables the shiftable aligning table to adjustably gage work-sheets of different characteristics so that a rapid shifting of the aligning table may be resorted to for properly locating the work-sheets for writing at a desired columnar position, instead of resorting to the comparatively slow operation of resetting the tabular or computing mechanism. Other objects of the invention are to provide means, for the purposes described, simple in construction, economical to manufacture, effective in operation, and easily applied to machines of standard construction.

According to one form of the invention, an aligning table or plate having a leading-edge gage and a side-edge gage is adjustably attached "for truing up purposes" to a bar extending from one end of the platen-frame to the other above the platen. This bar is provided with longitudinal slots in its ends, through which pass bolts extending through and held against rotation in substantially vertical slots in uprights forming parts of brackets attached to the ends of the platen-frame. It will be seen that the aligning table may be shifted to various line-space positions and various letter-space positions. The bar may be secured in any adjusted position with reference to the uprights by nuts threaded on the bolts, the nuts preferably being provided with knurled heads to facilitate turning the same.

To determine the letter-space position of the aligning table along the platen, provision may be made of adjustable stops on the face of the bar nearest to the uprights, so that, when the bar is moved in either direction, its limiting position will be determined by one of the stops being brought into engagement with one of the uprights. To determine the line-space position of the aligning table, use may be made of adjustable stops at both ends of the slots in the uprights, so that the limiting line-space positions of the table may be determined by adjustable stops at the opposite ends of the slots in the uprights with which the heads of the bolts contact when the aligning table is in either one of its limiting positions. It will be seen that, according to this form of the invention, provision is made for but two line-space positions of the aligning plate and two letter-space positions thereof.

To enable the work-sheet to be moved with the aligning table, means are provided for holding the work-sheet to the table, so that the table in its movement will carry the sheet along with it to another writing posi-

tion, thus eliminating handling or separate re-adjustment of the work-sheet after the table has been shifted to a new position.

According to another form of the invention, provision may be made for a greater number of line-space positions to which the aligning table may be set. To this end, provision may be made of a block for each upright slideable thereon, and through which passes the bolt extending through the two slots, the block being provided with a spring detent adapted to co-operate with recesses at line-space intervals on the uprights. It will be seen that the aligning plate, when the nuts have been released, may be rapidly shifted to move the work-sheet from one letter-space position to another, and from the original line-space position to another, determined by the detents entering recesses on the uprights, the aligning table then being secured into position by tightening the nuts.

Other features and advantages will hereinafter appear.

In the accompanying drawings,

Figure 1 is a fragmentary perspective view, showing one form of the invention applied to the platen-frame of an Underwood Standard typewriter.

Figure 2 is a perspective view, looking from the rear, of the novel structure removed from the platen-frame.

Figure 3 is a diagrammatic view, partly in section, of the structure shown in Figure 1.

Figure 4 is a fragmentary perspective view, parts being broken away to show the underlying structure, of a modified form of the means for adjusting the position of the aligning plate.

A cylindrical platen 11 is mounted on an axle 12, journaled in the ends 13 of a platen-frame 14. The platen-frame comprises the usual rear paper-table 15, having fingers 16 extending around the lower part of the platen.

A work-sheet or card 17 may be introduced either in the usual manner over the rear paper-table, or may be inserted at the front of the platen, and typing effected thereon by means of types 18 mounted on type-bars 19.

To enable the work-sheet or card to be properly positioned for typing thereon, provision in this instance is made of an aligning table 20, having a leading-edge gage 21 and a side-edge gage 22. When a work-sheet is introduced at the front of the platen, the feed-rolls (not shown) are in cast-off positions, and, for rapid work, it is found desirable to leave the feed-rolls in cast-off positions during the typing and to provide means on the aligning table to hold the work-sheet in position relative to the platen. For this purpose, a bracket 23 is

secured to the rear face of the aligning table 20, near its left-hand edge, by any suitable means, such as screws 24. The bracket 23 is preferably in the form of a bar or strap, bent around the side-edge gage 22 and extending substantially parallel to the front face of the aligning table 20. A leaf-spring 25 is secured at its middle to the inner end of the bracket 23 by suitable means, such as a screw 25^a, and is arched so that at one end it will engage the aligning table 20 near the side-edge gage 22, and at its other end the table 20 near its center, the ends of the spring 25 being upturned so as to facilitate the insertion of the work-sheet thereunder. It will be seen that the spring 25, engaging the work-sheet at two points spaced at a substantial distance apart, will hold the work-sheet firmly on the aligning table 20.

The aligning table 20 is supported by a bar 26, and to enable the leading-edge gage 21 on the table to be trued up with reference to the writing line, the connection between the table and the bar is effected by means of screws 27 extending through slots 28 in the table 20 and threaded into the bar 26. Preferably, the table 20 is countersunk around the slots 28 so as to enable the screw-heads to lie beneath the front face of the table 20, and prevent interference with the work-sheets placed on the table. The countersunk portions 29 may be formed by pressing the metal rearwardly around the slots, the result being that the table 20 will be slightly spaced from the bar 26 throughout the greater part of its extent.

To support the bar 26, provision is made of brackets 30, one at each end of the platen-frame. Preferably, each bracket 30 is made of a single bar or strip having a flat portion 31 to rest on the top of the corresponding end 13 of the platen-frame, the bracket being secured to the end of the platen-frame by means of screws 32 extending through the flat portion 31. At the forward end of the flat portion 31, the bracket 30 comprises a curved portion 33, extending rearwardly from the front end of the flat portion 31, and an upright 34 slightly inclined to the rear. It will be seen that the portion 33 extends rearwardly over the head of the screw 32 at the front of the flat portion 31. Provision is therefore made of an opening 35 above the forward screw 32 so as to enable manipulation of the screw by means of a tool inserted through said opening.

Each upright is provided with a slot 36 through which passes a bolt or screw 37, having a head 38 positioned at the rear of the upright and provided with flats 39 to engage the sides of the slot 36 to prevent turning of the bolt. The bolt 37 also passes through a slot 40 in the adjacent end of the bar 26; and the bar may be clamped in posi-

tion on the upright 34 by means of a nut 41 threaded on the end of the bolt, the head of the nut being knurled to facilitate manipulation thereof.

The form of the invention so far described is intended for use in shifting the aligning table 20 rapidly to move the work-sheet or card from one line-space position to another and from one letter-space position to another, and it is desirable to provide adjustable means for limiting the movement of the aligning table, both in the line-space and letter-space directions. To limit the letter-space movement of the aligning table 20, provision may be made of a stop 42 at the inner end of each slot on the bar 26 and guided by means of two screws 43 engaging in a slot 44, the screws when tightened serving to clamp the stop 42 in adjusted position. It will be seen that movement of the table 20 in either direction will be limited by engagement of one of the stops 42 with the adjacent upright 34. Movement of the aligning table 20 in the line-space direction may be limited by stops 45, one at each end of each of the slots 36, and adjustably secured on the uprights by means of screws 46 extending through slots 47 in the stops and threaded into the uprights.

According to one use of the invention, the aligning table is positioned, as shown in Figure 1, with the left-hand stop 42 in engagement with the left-hand upright 34 and the heads 38 of the screws 37 resting on the stops 45 at the lower ends of the slots 36. It should be understood that the various stops have been adjusted in accordance with the requirement of the cards to be used. A card 17 is then inserted at the front of the platen and gaged on the aligning table 20. It will be evident that the card 17 will ordinarily be brought beneath the spring 25 by insertion from the right under the right-hand end of the spring. After the typing has been effected on the line of the card positioned at the printing line, the nuts 41 are loosened and the aligning table shifted upwardly and to the right until the screw-heads are brought into engagement with the upper pair of stops 45 and the right-hand stop 42 is brought into engagement with the right-hand upright 34. The card 17, in this instance, is held on the aligning table 20 by means of the spring 25, so that the card is movable by and with the table; and thus, when the table 20 has been moved, the card 17 will be positioned so that typing may be effected on a lower line thereof and with the card positioned in a different field longitudinally of the platen from that first used. Also the work-sheet will have been rapidly moved from one writing position to another without moving the platen carriage.

Obviously, the structure shown in Figure 1 may be used for different purposes. For

example, the aligning table 20 may be shifted along the uprights in the line-space direction without any shifting thereof transversely of the machine, or it may be shifted 5 transversely of the machine without shifting in a line-space direction.

Heretofore when a typewriting machine has been set to accommodate work-sheets of one type by proper location of a side gage 10 and a tabulator stop, either within or without a certain zone, and it was desired to write upon a work-sheet of another type having different line-length characteristics, i. e., a different length of the writing line between a gaged side edge and the desired columnar writing position, it has been necessary to relocate either the side gage or the tabular mechanism, and perhaps also, in cases where computing was to be done, the 15 denomination-selectors. In the present device the same results are accomplished by adjusting the aligning table 20 for transverse movement between the uprights a distance equal to the difference between the 20 line-lengths of different work-sheets, so that an adjustable side gage is afforded for typing within the computing zone, or in one and the same columnar writing position, upon work-sheets of different line-lengths characteristics, the table 20 being moved to the 25 different adjusted positions to side gage the different work-sheets. Adjustment of the table 20 in the same manner is resorted to when it is desired to type in different columnar 30 positions upon work-sheets of uniform line-length characteristics as will be obvious. Likewise, the adjustments may be made to permit typing in different columnar positions upon work-sheets of different line-length characteristics. Also, the vertical 35 adjustment may be availed of for typing upon different work-sheets in different writing positions, so that when it is desired to type upon one work-sheet in a writing position determined by a certain letter-space 40 zone at a certain line elevation, and upon another work-sheet in a writing position determined by a different letter-space zone at a different line elevation, the aligning table 45 50 55 20 constitutes a combined line-finder and zone-finder and is with rapidity shiftable in a continuous movement relatively to the platen carriage from one adjusted writing position for one work-sheet to another adjusted writing position for the other work-sheet.

It may be necessary in some kinds of work to adjust the aligning table in more than two positions along the uprights. This requirement may be met by the modified form 60 of the invention, as shown in Figure 4. In this form, provision may be made of a frame 48 to fit over each of the uprights. The head 38 of the bolt associated with a corresponding upright lies in an opening

in the frame at the rear of the upright, and the threaded portion of the screw passes through an opening in the front wall of the frame. The threaded portion of the screw 37, which extends beyond the front wall of the frame 48, passes through the slot 40 at the adjacent end of the bar 26, so that the bar is slideable along the front face of the frame 48. It will be seen that tightening of the nut 41 will clamp the bar 26 and the frame 48 against the upright 34 and prevent their movement relative thereto. In this form of the invention, the stops 45 are omitted and the different vertical positions of the bar 26 are determined by means of 70 75 80 85 90 95 100 105 110 115 120 125 130 135 140 145 150 155 part of the work and a right-hand position thereof for another part of the work, thereby enabling a rapid adjustment from one of said positions to the other.

- 5 2. In a typewriting machine, in combination, a platen, a platen-frame, an aligning table, at the delivery side of the platen, to gage work-sheets on the platen, a bar secured to said table, adjustable means for locating said bar and consequently said aligning table in different mechanically-determined letter-space and line-space positions for different parts of the work, and means for holding said bar in any position to which it has been located. 70
- 10 3. In a typewriting machine, in combination, a platen, a platen-frame, an aligning table at the delivery side of the platen, a bar secured to said table, supporting means for said bar carried by the ends of the platen-frame and guiding said bar for longitudinal and vertical sliding movements, means for holding said bar in any position to which it has been shifted, and means for locating said bar in different letter-space and line-space positions, said locating means including adjustable stops to limit the movement of said bar longitudinally. 75
- 15 4. In a typewriting machine for use with computing mechanism, in combination, a platen, a platen-frame, an aligning table at the delivery side of the platen, means to detain a work-sheet on the table, a table-supporting device on each end of the platen-frame, permitting movements of the table transversely of the machine, and also in a direction to vary the line-space position of the table with reference to the printing line, means including stops adjustable to determine left and right-hand positions of the table and work-sheet thereon, so that computations in certain columns of the work-sheet may be varied without changing the setting of the computing mechanism, and a securing device, associated with each supporting device, to hold said table in adjusted position or to release the table and permit rapid adjustment thereof to another position of adjustment. 80
- 20 5. In a typewriting machine for use with computing mechanism to selectively compute numbers typed in different columns of a work-sheet, in combination, a platen on which a computing zone may be determined by said computing mechanism, a platen-carriage, an aligning table on said carriage at the delivery side of the platen, said table having thereon both side and leading-end gages for the work-sheet, and being bodily shiftable both laterally and vertically together with said gages thereon, permitting rapid shifting of the table to locate different columns of the work-sheet in register with said computing zone on the platen and to locate the work-sheet in different line-space positions, means for locating said table selectively at the letter-space positions in which the table serves to locate said columns on the work-sheet in register with the computing zone on the platen, means for locating said table selectively at any one of a multitude of mechanically-determined line-space positions, so that the bodily shifting of the aligning table may effect not only a change in the column in which the numbers are typed and computed, but numerous selective changes in the line in which the number to be computed is typed, and means for securing said table in any of said adjustments. 85
- 25 6. In a typewriting machine, in combination, a platen, a platen-frame, an aligning table, a bar secured to said table, and having longitudinal slots in its ends, uprights on the ends of the platen-frame, provided with substantially vertical
- 30 slots, pins extending through the slots in said bar and said uprights, to permit longitudinal and vertical movements of the aligning table, adjustable means to locate said bar in different mechanically-determined line-space positions for varying the line-space and columnar position of a work-sheet on the aligning table without line-spacing the platen or shifting the carriage in a letter-space direction and letter-space positions, and means to clamp said bar and said uprights to prevent movement of the bar with respect to the uprights. 90
- 35 7. In a typewriting machine for use with mechanism for computing selectively in different columns of a work-sheet, in combination, a front-strike platen, a platen-frame, a combined line-finding and zone-finding aligning table mounted at the delivery side of the platen, and having fixed thereon a leading-edge gage and a side-edge gage, means for detaining the work-sheet on said table, a table-supporting device at each end of the platen-frame permitting bodily movement of the table transversely of the machine and also towards and away from the printing line, means for mechanically locating the table with said gages in different line-space and letter-space positions, and a releasable securing device associated with each supporting device to hold the table against movement in either of said positions. 100
- 40 8. In a typewriting machine, in combination, a platen, a platen-frame, an aligning table, and means to facilitate a rapid adjustment of said table, both as to line-space position with reference to the printing line and as to letter-space position along the platen, said means comprising a supporting device at each end of the platen-frame, having a pin-and-slot connection to enable line-space adjustment of the table, and a pin-and-slot connection to enable letter-space adjustment. 105
- 45 9. In a typewriting machine, in combination, a traveling carriage, a platen, a platen-frame, an aligning table, a bar secured to said table, and having longitudinal slots in its ends, uprights on the ends of the platen-frame, provided with substantially vertical

of the table, adjustable means to determine different line-space positions of the table, and a holding device adapted, when rendered effective, to prevent movement of the table for either line-space or letter-space adjustment.

9. In a typewriting machine for use with mechanism for computing selectively numbers typed in different columns of a work-sheet, in combination, a platen, a traveling carriage therefor, an aligning table above the platen, a support extending upwardly from each end of the carriage, a connection between said table and each of said supports, permitting movement of the table in line-space direction or in letter-space direction on the support, so that the table may be shifted to different letter-space positions, either with or without changing the line-space position of the table, to vary the computations of numbers printed in the various columns, and a clamping device, comprising a single manually-operable controlling member, associated with each of said connections, adapted, when actuated, to hold the table against such movements on the corresponding support.

10. In a typewriting machine, in combination, a platen, a platen-frame, an aligning table above the platen, a support extending upwardly from each end of the platen-frame, means to connect said table with each of said supports, comprising a frame mounted on the support and shiftable therealong, said table being shiftable in letter-space direction with reference to each of said frames, and yieldable detent means whereby each frame may be yieldably held at different positions on the corresponding support.

11. In a typewriting machine, in combination, a platen, a platen-frame, an aligning table above the platen, a support extending upwardly from each end of the platen-frame, means to connect said table with each of said supports, comprising a frame mounted on the support and shiftable therealong, said table being shiftable in letter-space direction with reference to said frames, yieldable detent means whereby each frame may be yieldably held at different positions on the corresponding support, and means associated with each of said connecting means to clamp the corresponding frame and said table against movement with reference to the support.

12. In a typewriting machine, in combination, a platen, a platen-frame, an aligning table above the platen, a bar secured to said table, supporting means for said bar, carried by the ends of the platen-frame and guiding said bar for longitudinal and vertical sliding movements, and yieldable detent means for supporting the bar in different positions vertically.

13. In a typewriting machine, in combination, a platen, a platen-frame, an aligning

table above the platen, a bar secured to said table, supporting means for said bar, carried by the ends of the platen-frame and guiding said bar for longitudinal and vertical sliding movements, yieldable detent means for supporting the bar in different positions vertically, and means for clamping said bar in any position to which it has been shifted.

14. In a typewriting machine, in combination, a platen, a platen-frame, an aligning table, a bar secured to said table and having longitudinal slots in its ends, uprights on the ends of the platen-frame and provided with substantially vertical slots, pins extending through the slots in said bar in said uprights, to permit longitudinal and vertical movements of the aligning table, and yieldable detent means to detain the pins in different positions along the slots in said uprights.

15. In a typewriting machine, in combination, a platen, a platen-frame, an aligning table, a bar secured to said table and having longitudinal slots in its ends, uprights on the ends of the platen-frame, provided with substantially vertical slots, bolts extending through the slots in said bar in said uprights, said bolts having flats thereon to cooperate with the sides of certain of said slots to prevent turning of the bolts, yieldable detent means to hold the bolts in different positions in the vertical slots, and nuts on the bolts whereby said bar and said uprights may be clamped, so as to prevent movement of the bar with respect to the uprights.

16. In a typewriting machine, in combination, a platen, a platen-frame, and means to facilitate writing on one line of a work-sheet when the latter is over one field of the platen, and on another line when the work-sheet is over another field of the platen, said means comprising an aligning table having leading-edge and side-edge gages, supporting means for said table, adapted to permit a rapid change vertically from one line-space position to another, and horizontally from one letter-space position to another, yieldable detent means to determine a plurality of line-space positions for said table, and means to secure said aligning table in adjusted position.

17. In a typewriting machine, in combination, a platen, a platen-frame, an aligning table, a table-supporting device on each end of the platen-frame, permitting movements of the table transversely of the machine, and also in a direction to vary the line-space position of the table with reference to the printing line, means, including yieldable detent devices, to determine different adjusted positions of said table, and a securing device associated with each supporting device and adapted to hold said table against movement in either of said directions, or to release the table and permit rapid adjustment thereof.

18. In a typewriting machine, in combina-

- tion, a platen, a front paper-table, supports at the delivery side of the platen having recesses at regular intervals, and connections between said table and said supports, comprising yieldable detents to co-operate with said recesses and arranged to ride out of the recesses when pressure is applied to the table to shift it to another position.
19. In a typewriting machine, in combination, two parallel members having recesses at regular intervals, a bar extending across said parallel members, and connections between said bar and said members, comprising yieldable detents to enter said recesses and arranged to ride out of the recesses when pressure is applied to shift the bar to another position.
20. In a typewriting machine, the combination with a front-strike platen, of a platen-carriage, and a line-finder or means for locating a work-sheet, comprising a supporting device to which the work-sheet is held, said sheet-supporting device being at the delivery side of the platen, standards at the opposite ends of the carriage, said supporting device mounted for up-and-down movement on said standards, means determining the bottom location of said sheet-supporting device, and stops settable at numerous line-spaced locations upon said standards for arresting the upward movement of said sheet-supporting device in correct position to begin the typing at a predetermined line upon the work-sheet.
21. In a typewriting machine, the combination with a front-strike platen, of a platen-carriage, and a line-finding or means for locating a work-sheet, comprising a supporting device to which the work-sheet is held, said sheet-supporting device including a table at the delivery side of the platen, standards secured at the opposite ends of the carriage, pin-and-slot means on said standards affording up-and-down movement of said sheet-supporting device within fixed maximum limits to determine top and bottom locations of said sheet-supporting device, stops settable to numerous line-space locations intermediate said fixed limits for arresting the upward movement of said sheet-supporting device in correct position to begin the typing at a predetermined line upon the work-sheet, and means for securing the sheet-supporting device where adjusted.
22. In a typewriting machine, the combination with a front-strike platen, of a platen-carriage, and a zone-finder or means for locating a work-sheet, comprising a supporting device to which the work-sheet is held, said sheet-supporting device being at the delivery side of the platen, standards at the opposite ends of the carriage, said supporting device being mounted for end-to-end movement on said standards, means de-
- termining one end location of said sheet-supporting device, and a stop arresting the opposite endward movement of said sheet-supporting device in correct position to begin the typing at a predetermined zone upon the work-sheet.
23. In a typewriting machine, the combination with a front-strike platen, of a platen-carriage, and a combined line-finder and zone-finder or means for locating a work-sheet, comprising a supporting device to which the work-sheet is held, said sheet-supporting device being at the delivery side of the platen, standards at the opposite ends of the carriage, said supporting device being mounted for up-and-down and end-to-end movement on said standards, means determining the bottom location and one end location of said sheet-supporting device, and stops arresting the upward and opposite endward movement of said sheet-supporting device in correct position to begin the typing at a predetermined line and zone upon the work-sheet, said stops being adjustable to vary the up-and-down and end-to-end movement of the sheet-supporting device.
24. In a typewriting machine, the combination with a front-strike platen, of a platen-carriage, and a combined line-finder and zone-finder, or means for locating a work-sheet, comprising a sheet-supporting device mounted at the delivery side of the platen for up-and-down and end-to-end movement, means for holding the work-sheet to the supporting device, means affording a continuous unimpeded endward and upward movement of the sheet-supporting device to draw the work-sheet to predetermined typing position on a different line and in a different zone of the work-sheet, and adjustable arresting means determining the limits of said continuous movement.
25. In a typewriting machine, in combination, a platen, a platen-frame, an aligning table at the delivery side of the platen, brackets secured to the ends of said platen-frame above the platen, a bar secured to said table, pin-and-slot means co-operative between said bar and said brackets for mounting the table between the brackets for movement both longitudinally and transversely of the platen, and independently thereof, adjustable stops determining the limits of said movement in each of said directions, side-edge and top-edge gages on said table effective in different positions of the table to locate work-sheets of different line-length and head-spacing with the respective writing positions thereof in alignment with the same point on the platen without movement of the platen, and means for securing said bar to said brackets to hold the table in adjusted position.
